IRONING BOARD LEG AND BRACE STRUCTURE

Filed Nov. 6, 1946

UNITED STATES PATENT OFFICE

2,445,598

IRONING BOARD LEG AND BRACE
STRUCTUREEarl C. Booth, Columbus, Ind., assignor to Noblitt-
Sparks Industries, Inc., Columbus, Ind., a cor-
poration of Indiana

Application November 6, 1946, Serial No. 708,065

6 Claims. (Cl. 38—117)

1

My invention relates to collapsible ironing boards and more particularly to an ironing board having its front end and rear legs interconnected by links and provided with a strut or brace which extends between the rear end of the ironing board top and the lower end of the front leg and which can be released to permit the legs to be folded against the top. An example of such an ironing board is found in my co-pending patent application Serial No. 646,367 filed February 8, 1946.

It is an object of this invention to simplify and improve the construction of ironing boards of the type described, to lessen the cost of manufacture, and to provide a more rigid structure.

In carrying out my invention, instead of attaching directly to the front leg the links which interconnect the front and rear legs, I connect the front ends of such links to the strut or brace which holds the legs extended. The lower end of such brace is attached to the front leg adjacent the lower end thereof, and the means employed to interconnect the front leg with the brace and the brace in turn with the links is such as will permit the relative movement which occurs between those parts when the legs are collapsed or extended. Desirably, the points at which the brace is respectively connected to the links and to the front legs are relatively close together in order to reduce the magnitude of any stresses imposed on the brace by the links.

The accompanying drawing illustrates my invention:

Fig. 1 is a side elevation of an ironing board in extended condition; Fig. 2 is a fragmental vertical view through the lower end of the front leg showing a preferred method of interconnecting the brace with the links and front leg; Fig. 3 is a fragmental plan view illustrating the construction of Fig. 2; Fig. 4 is a fragmental view similar to Fig. 2 illustrating the condition of the links and brace prior to the final step in their assembly; Fig. 5 is a fragmental plan view similar to Fig. 3 illustrating a modified form of construction; Fig. 6 is a vertical section through the modified structure of Fig. 5; Fig. 7 is a fragmental plan view illustrating a further modification; Fig. 8 is a vertical section through the structure of Fig. 7; and Fig. 9 is a sectional view illustrating a detail of construction employed in the structure of Figs. 7 and 8.

The ironing board illustrated in Fig. 1 comprises a top 10, rear legs 11 pivoted to the top adjacent the rear end thereof, and a front leg 12 pivoted to the top at an intermediate point. The free end of the front leg 12 is connected to inter-

2

mediate points of the rear legs 11 by legs 13, the lengths of such links and the points of their attachment to the rear legs 11 being such that the front and rear legs will swing jointly from the extended position illustrated in Fig. 1 to a collapsed position adjacent the lower face of the top 10. To hold the legs in extended position, a brace 14 is connected to the free end of the front leg 12 and extends obliquely upwardly for releasable connection to the top 10 adjacent the rear end thereof. In the particular structure illustrated in Fig. 1, the releasable connection between the upper end of the brace 14 and the top 10 is effected through the medium of a guide 15 which is pivoted to the top and which slidably receives the upper end of the brace 14. Upward movement of the brace 14 in the guide 15 is limited by engagement of the lower end of the guide with a fixed abutment 16 on the brace; while downward movement of the brace in the guide 15 when the legs are extended is limited by engagement of a second abutment 17 on the brace 14 with the upper end of the guide 15. The latter engagement is releasable, by moving the rear end of the brace 14 upwardly to permit the abutment 17 to enter the guide 15, thus in turn permitting the legs to swing against the lower surface of the top 10.

The above construction is described merely by way of example, as this invention is not concerned with any particular means for holding the legs in extended position. Instead, this invention is directed to the means employed to interconnect the lower ends of the links 13, brace 14, and front leg 12.

35 In the preferred form of construction, the front leg 12 is formed of a length of metal tubing bent into a general U-shape, the ends of the tubing being pivotally connected to the board 10, as indicated at 18 in Fig. 1. When such a leg is used, the wall of the tubing at its outer end is provided with an opening 21 through which the front end of the brace 14 extends into the interior of the tube. Within the tube, the front end of the brace is provided with an opening which loosely receives a pin or rivet 22 extending diametrically across the tube. If desired, the tube may be provided with a foot 23 of soft rubber or similar material; and if such a foot is employed, it is provided with an opening 24 for the end of the link 13 and may be held in place by the rivet or bolt 22, as indicated in Figs. 2 and 6.

40 In the construction illustrated in Figs. 2, 3, and 4, the links 13 are formed of single metal rod which is bent into a general U-shape and has its ends secured to the rear legs 11, as indi-

cated at 25 in Fig. 1. The curved intermediate portion 27, which joins the front ends of the links 13, is received in a transverse groove 28 (Fig. 4) provided in the lower surface of the brace 14 adjacent its point of connection with the front leg 12. As will be clear from Fig. 4, the groove 28 has a depth somewhat greater than the radius of the rod from which the links 13 are formed; and after the curved intermediate portion is placed in the groove 28, the material at the sides of such groove is displaced inwardly, as by a staking operation, to form lips 29 which overlie the link-portion 27 and prevent its removal from the groove while, at the same time, leaving the links free to swing about the axis of the groove to the limited extent necessary to permit collapse and extension of the legs 11 and 12.

In the modified arrangement shown in Fig. 5, the brace 14 is flattened in a vertical plane, as indicated at 31, in rear of its point of connection to the front leg 12. The links 13 are made of separate rods, and their front ends are flattened and disposed on opposite sides of the flattened portion of the brace 14, as shown at 32 in Fig. 5. A rivet or bolt 34 extending through the flattened portions 32 and 31 of the links 13 and brace 14 serves to secure them together while permitting them to swing about the axis of the bolt or rivet.

In the further modification shown in Figs. 7, 8, and 9, the links 13 are formed of a single rod joined by an intermediate portion 27, as in the arrangement illustrated in Figs. 2, 3, and 4. In addition, the brace 14 is provided near its outer end with a downwardly opening transverse groove 28, also as in the construction of Figs. 2, 3, and 4. In this instance, however, a separate element in the form of a sheet-metal clip 36 is employed to secure the intermediate link-portion 27 in the groove 28. As will be clear from the drawing, such clip has a body portion which bridges the open side of the groove 28 and end portions 37 which are bent to embrace the brace 14 on opposite sides of such groove.

All constructions described have the advantage that a single means is employed for the pivotal mounting of both of the links 13. Further, by attaching the links to the brace 14 rather than to the front leg 12, the problem of mounting the links on a common axis is greatly simplified.

I claim as my invention:

1. In an ironing board, a top, rear legs pivotally connected to said top near one end thereof, a front leg pivoted to said top at an intermediate point thereon, a brace member pivotally connected to said front leg near the free end thereof and extending upwardly to a point adjacent the rear end of said top, a link associated with

each of said rear legs and having one end connected thereto and the other end connected to said brace adjacent the point at which said brace is connected to the front leg, and means for releasably securing the upper end of said brace to said top to maintain the legs in extended positions.

2. The invention set forth in claim 1 with the addition that said links are formed of a single metal rod bent into a general U-shape and having an intermediate portion which is pivotally mounted in said brace.

3. The invention set forth in claim 1 with the addition that said links are formed of a single metal rod bent into a general U-shape and having an intermediate portion, said brace being provided with a transverse groove in which said intermediate portion is pivotally received, and means for holding said intermediate leg in said groove.

4. The invention set forth in claim 1 with the addition that said links are formed of a single metal rod bent into a general U-shape and having an intermediate portion, said brace being provided with a transverse groove in which said intermediate portion is pivotally received, a portion of the material of said brace at one side of said groove being displaced to overlie said intermediate rod-portion and retain it in said groove.

5. The invention set forth in claim 1 with the addition that said links are formed of a single metal rod bent into a general U-shape and having an intermediate portion, said brace being provided with a transverse groove in which said intermediate portion is pivotally received, and a sheet-metal clip having a body portion overlying said groove and ears embracing the brace at the sides of the groove.

6. In an ironing board, a top, rear legs pivotally connected to said top near one end thereof, a front leg formed of metal tubing bent into a general U-shape and having its ends pivoted to said top on a common axis intermediate the length of the top, means interconnecting said front and rear legs for joint movement between collapsed positions and extended positions in which they act as a support for said top, and means for releasably retaining said legs in extended position, said means comprising a brace, said tubular front leg being provided near its free end with an opening in said wall, and a pin extending across the interior of said leg adjacent the opening in the wall thereof, said brace extending through said opening into the interior of the tube and being there provided with an opening loosely receiving said pin.

EARL C. BOOTH.

Certificate of Correction

Patent No. 2,445,598.

July 20, 1948.

EARL C. BOOTH

It is hereby certified that error appears in the printed specification of the above numbered patent requiring correction as follows: Column 2, line 1, for "legs 13" read *links 13*; and that the said Letters Patent should be read with this correction therein that the same may conform to the record of the case in the Patent Office.

Signed and sealed this 28th day of September, A. D. 1948.
